UNITED STATES PATENT OFFICE

ALVIN H. BAER, OF WAYNESBORO, PENNSYLVANIA, ASSIGNOR TO FRICK COMPANY, OF WAYNESBORO, PENNSYLVANIA, A CORPORATION OF PENNSYLVANIA

EVAPORATOR

Application filed June 4, 1932. Serial No. 615,415.

This invention deals with evaporators for refrigerating systems, and its object is to provide for better circulation of refrigerant.

A further object is to provide an evaporator requiring small head room for its installation.

Further objects and advantages will become apparent as the description proceeds.

Referring to the accompanying drawing, 10 which is made a part hereof and on which similar reference characters indicate similar parts,

Figure 1 is an end view of the evaporator as it would appear when installed near the 15 top of a refrigerating car,

Figure 2, a side elevation of the evaporator,

Figure 3, a plan view of the same, and 20 Figure 4, a view similar to Figure 1 of a slightly modified form of the evaporator.

In the drawing numeral 10 indicates the ceiling of a refrigerator car in which the evaporator may be installed. The evaporator itself consists of upper and lower headers 11 and 12, connected by bowed riser tubes 13 and 14. In the form shown in Figures 1 to 3, there are two sets of these tubes, the tubes of one set being considerably longer than those of the other set. The 25 headers 11 and 12 are placed relatively close together and the bowed tubes extend laterally so as to provide a relatively long channel through which the refrigerant passes from the lower to the upper header. The upper header is larger than the lower since the refrigerant will be sucked from this header, the reduced pressure tending to aid in the evaporation of the refrigerant.

Short bent tubes 19 are connected to the 40 ends of the headers at or near the bottoms of the headers and provide for return to the lower header of the liquid entrained with the gas and brought into the upper header. These tubes are preferably covered with 45 some heat insulating material 21.

In operation the refrigerant will absorb heat and evaporate to a gas; the gas will flow upwards through the liquid from the point where it forms, which may be at any 50 point on the exposed surface of the bent

tubes, as well as the headers. As gas is drawn away from the top header by the suction of the refrigerating machine or compressor, a slight reduction in pressure is created there, and the small bubbles or quantities of gas formed throughout the bent tubes will flow upwards partly because of this fact and partly because of the reason of difference in their weight in respect to the weight of the liquid; just as air bubbles 55 will rise to the top surface of a pail of water.

This will not, however, serve to create a self circulating system entirely, because the gas bubbles will join each other as they move along, form larger quantities and tend to 60 push some of the liquid ahead of them, through the bent tubes. Now if there is provided a suitable return passage for the liquid that is lifted towards the upper header where it will not be disturbed or retarded 65 by the tendency of gas flowing upwards, the excess liquid pushed into the upper header will flow back to the lower header, just as water circulates in a water tube boiler with drums above and below, to generate steam. 70

The tubes at one or both ends of the headers, connect the lower point of the upper header with a lower point on the end of the lower header. When the evaporator is charged 75 with liquid it will be filled up to the lower level of the upper header, and perhaps a small quantity in the lower side of that header. Liquid pushed upwards will flow back to the lower header at the end. Because of the exposed surface of the lower header also, absorbing heat and creating gas, 80 the bent tubes are connected to the upper part of that header to make the upward passage of this gas, through the bent tubes, 85 easy. The return tube at the end of the header connects to the lower parts of the lower header, so as to make the return of the liquid downward quite easy. The return tubes are covered with insulation so

that they will not absorb heat, and create gas which would tend to flow upward and interfere to some extent with the free downward circulation of the liquid.

There is an advantage in a refrigerating 100

plant for vehicles in having the cooling unit or evaporator located along the ceiling of the refrigerated space as it insures uniform cooling of the space. A special advantage is secured in that this form of evaporator may be installed where there is a very small head room. Heretofore such flooded type of evaporators have been narrow and high. My evaporator occupies very small head room and by making the width much greater than the over-all height, ample provision is had for heat transfer between the evaporator and the surrounding media while the evaporator unit may be installed in a relatively small space.

In the form of evaporator shown in Figure 4 there are provided upper and lower headers 15 and 16, the upper header being considerably larger than the lower header. Bowed tubes 17 connect the headers, these tubes being bent as shown at 18 and entering the lower header in the top portion of the header. The bent portions of the headers provide a somewhat more steeply inclined passage from the lower header as the refrigerant leaves the header. Short insulated tubes 20 connect the ends of the lower with the ends of the upper header to provide for a return to the lower header of any liquid refrigerant carried over by the entraining gas. In this form of evaporator only one set of tubes is provided at each side of the headers instead of the two sets as shown in Figure 1. This form of evaporator is somewhat cheaper than the form shown in Figure 1. In both cases, however, the headers are placed close together and the bowed tubes which constitute risers extend relatively wide distances laterally to provide long heat transfer channels for cooling the media surrounding the evaporator.

It will be obvious to those skilled in the art that various changes may be made in my device without departing from the spirit of the invention and therefore, I do not limit myself to what is shown in the drawing and described in the specification, but only as indicated by the appended claims.

Having thus fully described my said invention, what I claim as new and desire to secure by Letters Patent, is:

1. An evaporator for a refrigerating unit comprising a lower header and an upper header, the upper header being larger than the lower header, and a series of bowed tubes connecting the lower with the upper header, and a pair of short tubes connecting the ends of the lower with the ends of the upper headers, substantially as set forth.
2. An evaporator for a refrigerating unit comprising a lower header and an upper header, the upper header being larger than the lower header, a series of bowed tubes connecting the lower with the upper header, and a pair of short tubes connecting the ends of

the lower with the ends of the upper headers, and a second series of shorter bowed tubes connecting the lower and the upper headers and positioned within the space defined by the first series of bowed tubes, substantially as set forth.

3. An evaporator comprising an upper and a lower header lying adjacent each other, a plurality of laterally extending bowed tubes connecting said headers, and a pair of short insulated tubes connecting the ends of said headers, said short tubes being attached near the bottoms of said headers and providing conduits for returning liquid refrigerant from the upper to the lower header, substantially as set forth.

4. An evaporator comprising an upper and a lower header, positioned approximately against each other, a plurality of relatively long laterally extending bowed tubes connecting said headers, and a pair of relatively short insulated tubes connecting the ends of said headers, said short tubes being attached near the bottoms of said headers and providing conduits for returning liquid refrigerant from the upper to the lower header, substantially as set forth.

5. An evaporator comprising an upper and a lower header, a plurality of bowed tubes connecting said headers, said tubes being connected to said headers in the upper half of the headers, and a pair of liquid refrigerant return tubes connecting said headers, said tubes being connected to the headers in the lower half of the headers, substantially as set forth.

6. An evaporator comprising an upper and a lower header, a plurality of bowed tubes connecting said headers, said tubes being connected to said headers in the upper half of the headers, and a pair of liquid refrigerant return tubes connecting said headers, said tubes being connected to the headers in the lower half of the headers, said last-named tubes being covered with a heat insulating media, substantially as set forth.

7. An evaporator comprising an upper and a lower header, laterally bent riser tubes connecting said headers, and insulated tubes connecting the ends of the upper with the ends of the lower header for returning liquid refrigerant from the upper to the lower header, substantially as set forth.

8. An evaporator comprising an upper and a lower header, laterally extending bent riser tubes connecting said headers, and short insulated tubes connecting the ends of the upper with the ends of the lower header for returning liquid refrigerant from the upper to the lower header, said riser tubes being relatively long to provide a gradual upwardly inclined channel for evaporating refrigerant and said return tubes being relatively short to provide quick return of the refrigerant.

- erant without evaporation therein, substantially as set forth.
9. An evaporator comprising an upper and a lower header, laterally extending bent 5 riser tubes connecting said headers, and insulated tubes connecting the ends of the upper with the ends of the lower header for returning liquid refrigerant from the upper to the lower header, said riser tubes being 10 relatively long to provide a long upwardly inclined channel for evaporating refrigerant and said return tubes being relatively short to provide quick return of refrigerant without evaporation therein, said riser tubes being 15 connected in the upper half of the headers and said short return tubes being connected in the lower half of the headers and adjacent the ends thereof, substantially as set forth.
- 20 10. An evaporator adapted for use in a chamber having low head room comprising upper and lower headers positioned relative-

ly close together, a plurality of groups of bowed tubes connecting the said headers, a second group bowed tubes shorter in length than the first named tubes and confined in the space defined by the first group of tubes, 70 both of said groups of tubes extending laterally to a distance substantially greater than the vertical distance between the headers, substantially as set forth.

11. An evaporator adapted to be positioned in a chamber having relatively low head room comprising upper and lower headers positioned relatively close together, a plurality of bowed tubes connecting said 75 headers and extending in both directions laterally from the headers to a distance considerably greater than the distance between the headers to provide a relatively long channel for passage of the refrigerant from the lower to the upper header, substantially as set forth.
